UNITED STATES PATENT OFFICE.

EDWARD M. PEARSON AND CHARLES W. FRANZHEIM, OF WHEELING, W. VA.
ASSIGNORS TO THE WHEELING POTTERY COMPANY, OF SAME PLACE.

DESIGN FOR A PITCHER.

SPECIFICATION forming part of Design No. 13,633, dated July 11, 1882.

Application filed May 13, 1882. Term of patent 14 years.

To all whom it may concern:

Be it known that we, EDWARD M. PEARSON and CHARLES W. FRANZHEIM, of Wheeling, in the county of Ohio and State of West Virginia, have produced a new and original Design for Pitchers; and we do hereby declare that the following is a full, clear, and exact description of the invention, which will enable others skilled in the art to which it appertains to make and use the same, reference being had to the accompanying drawings, which form a part of this specification.

This invention relates to designs for water and other pitchers; and it consists in certain new and useful designs for the ornamentation of the same.

In the drawings, Figure 1 is a side view; Fig. 2, a vertical sectional view.

Referring by letter to the drawings, A designates the body of the pitcher, which is provided, near its bottom, with an annular groove, B, above which is a like projection or ridge, C, from which the sides D converge upwardly and are perfectly plain, and at the top is formed another circumferential ridge, E, above which the edge F is curved.

G is a perfectly plain mouth or spout, and H is the handle, the corners of the latter, I, being corrugated, as shown.

J designates the top of the pitcher, which is

somewhat conical in shape, having a plain upright lower edge, K, above which it is inwardly and upwardly curved, as at L, to a circumferential point or ridge, M, above which the sides are curved inwardly and convexly to a plain 35 elevation, N.

O is an ornamented elevation above the latter, from which the sides extend straight upwardly and inwardly, as at P, when they form a dome, Q, surmounted by an ornamental 40 knob, R, having the plain base S and projecting circumferential notched edges T U, between which the surface V is corrugated and above which it rises to a point, W.

Our improved design, when embodied in a 45 pitcher, presents and imparts thereto an attractive, neat, and beautiful appearance.

We claim and desire to secure by Letters Patent—

The herein-described design for pitchers, 50 substantially as shown and specified.

In testimony that we claim the foregoing as our own we have hereto affixed our signatures in presence of two witnesses.

EDWARD M. PEARSON.
CHARLES W. FRANZHEIM.
